UNITED STATES PATENT OFFICE.

WILLIAM FEHR, OF PHILADELPHIA, PENNSYLVANIA, ASSIGNOR TO STEEL HEDDLE MANUFACTURING COMPANY, OF PHILADELPHIA, PENNSYLVANIA, A CORPORATION OF PENNSYLVANIA.

GRIPPING MECHANISM FOR FEEDING METAL STRIPS, &c.

SPECIFICATION forming part of Letters Patent No. 699,508, dated May 6, 1902.

Application filed December 20, 1901. Serial No. 86,635. (No model.)

To all whom it may concern:

Be it known that I, WILLIAM FEHR, a citizen of the United States, residing at the city of Philadelphia, in the county of Philadelphia and State of Pennsylvania, have invented certain new and useful Improvements in Gripping Mechanism for Feeding Metal Strips and the Like, of which the following is a specification.

10 My invention has relation to a mechanism for gripping and positively feeding metallic strips, rods, &c., through a machine adapted to manipulate the strip in the desired manner; and in such connection it relates to the 15 general construction and arrangement of such a mechanism.

Heretofore it has been the custom in feeding strips, bars, or rods of metal through a machine to employ means which push or feed 20 the rod toward the point of manipulation. Such feeding mechanisms are defective, for if the article is pushed forward any accidental blocking of the travel of the article results in the buckling or bending of the strip and the 25 production of strips of metal of varying lengths. Again, where the whole strip or bar was to be severed into successive portions of predetermined lengths and the strip was fed forward by rollers it was difficult to accurately 30 gage or limit the feed of the strip.

The principal objects of my present invention are, first, to provide a gripping and feeding means for heddle-making and other machines which is adapted to grip the metal 35 strip or rod to be fed either just before the mechanism completes its movement in one direction or at the moment when such movement is completed, and, second, to provide a combined gripping and feeding means which 40 is adapted not only to grip the metal strip or rod just before or at the moment of completion of the movement in one direction of said means, but also to release the metal strip or rod from said gripping and feeding means just before or at the moment of completion of the 45 said movement in the opposite direction of the said means.

The nature and scope of my invention will be more fully understood from the following 50 description, taken in connection with the ac-

companying drawings, forming part hereof, in which—

Figure 1 is a side elevational view of a gripping and feeding mechanism for metal strips embodying main features of my invention. 55 Fig. 2 is a top or plan view of the same. Fig. 3 is a side elevational view, enlarged, illustrating the gripping mechanism with the front plate broken away and with the jaws in closed position. Fig. 4 is a view similar 60 to Fig. 3, but illustrating the feeding-jaws in open position. Fig. 5 is a top or plan view of Fig. 3, and Fig. 6 is a vertical sectional view taken on the line 6 6 of Fig. 3.

Referring to Figs. 1 and 2 of the drawings, 65 A represents a part of the machine through which the strip B is to be drawn after certain manipulations. The part A of the machine which is represented in the drawings is that wherein the shearing or cutting off of the 70 strip B is accomplished. Adjacent to and in front of the shears B' extends a guide-rail a, on which is adapted to reciprocate a gripping mechanism D of a construction to be herein-after more fully explained. The mechanism 75 D is inclosed in a case D', which slides back and forth on the rail a, being moved by a rod or shaft a', which in turn is reciprocated by the oscillating or rocking arm a². The forward movement of the case D' toward the 80 machine A is limited by a stop a³, located on the rail a near the machine A, and the rearward movement of the case D' is likewise limited by a stop a⁴ on the rail a. These stops a³ and a⁴ not only act as a gage to limit 85 the movement of the gripping mechanism, and hence the length of the strip B drawn out of the machine A, but also serve an additional function in controlling the gripping mechanism, as hereinafter explained. 90

Referring now to Figs. 3, 4, 5, and 6, the preferred arrangement and construction of the gripping mechanism D is as follows: Within the case D' and near its forward end are pivoted the two gripping-jaws b, the forward ends of which project slightly beyond the forward end of the case D'. The rear end of each jaw b is slotted, as at b', to receive the cross-pintles b², each pintle being formed at one end of a link or toggle b³, the said toggles 95 100

or links b^3 also having at their other or inner ends the cross-pintles b^4 , oscillating in the notches or recesses b^5 , formed in the head d of the rod or shaft a' . The jaws b are pivoted 5 at points b^6 near to the forward or gripping portions of the jaws, and the rear ends of the jaws b are normally pressed inward toward each other by the springs b^7 or by any suitable mechanism. When the links or toggles 10 b^3 occupy a position substantially at right angles to the head d of the shaft or rod a' , as illustrated in Fig. 3, then the rear ends of the jaws b are thrown outward by the links or toggles b^3 against the inward pressure of the 15 springs b^7 , and the forward or gripping ends of the jaws b are tightly clamped together. When, however, the links or toggles b^3 occupy an inclined position to the head d , as 20 illustrated in Fig. 4, then the rear ends of the jaws b are thrown inward by the springs b^7 , and the gripping ends of the jaws b are separated. To control the position of the toggles or links b^3 , and consequently to control the opening and closing of the gripping ends of 25 the jaws b , it is necessary that the head d of the shaft or rod a' shall have a movement within the case D' irrespective or independent of any movement of the case D' . As hereinbefore explained, at the forward end 30 of its movement the case D' abuts against a stop a^8 , and in its rearward movement the case also abuts against the stop a^4 . At each of these points the shaft or rod a' has not completed its stroke or movement, but continues 35 for a slight distance forward or backward after the case D' has ceased to move. This additional movement of the shaft or rod a' is transmitted to its head d within the case D' , and hence the necessary movement of the 40 toggles or links b^3 is secured. To prevent accidental movement of the head d within the case D' , as well as to lock the head d to the case during the entire movement of the case D' , there are provided at the side of the case 45 D' two spring-controlled pins e and e' , each of which traverses the case and has a beveled bearing end e^2 . The head d is provided on its side with two grooves d' and d^2 , the forward one, d' , of which is adapted to be engaged 50 by the beveled end e^2 of the forward pin e during the entire rearward movement of the case D' , while the other groove d^2 is adapted to be engaged by the other pin e' during the entire forward movement of the case 55 D' . When this case D' abuts against the stop a^8 , the head d is shifted so that the pin e' comes out of engagement with the groove d^2 , and the other groove d' is shifted into engagement with the other pin e , while when the 60 case D' strikes the stop a^4 then the head d is shifted so that the pin e is thrown out of the groove d' and the pin e' is thrown into engagement with the groove d^2 . It will thus be seen that during the movement of the case D' 65 toward the machine A the position of the parts within the case D' remains as illustrated in Fig. 4 until the case D' stops by

abutting against the stop a^8 . The movement forward of the head d of the shaft a within the case D' now causes the parts to occupy 70 the position illustrated in Fig. 3. The parts are locked in this position during the entire return movement of the case D' , which at the end of its movement abuts against the stop a^4 , and then the head d of the shaft a continues 75 to move backward within the case D' to move the parts within the case again to the position as illustrated in Fig. 4. It will be readily understood that there is a positive movement to the jaws b only after the case 80 D' has reached the limit of either its forward or rearward movement, and as the jaws b are clamped to the strip B during the entire movement of the case D' the length of the successive strips dragged out of the machine 85 by the case D' will always remain the same so long as the stops a^8 and a^4 remain fixed.

As hereinbefore explained, the strip B is gripped by the feeding mechanism D either just before the mechanism completes its movement in one direction or at the moment of completion of said movement, and the strip is also released from said feeding mechanism just before or at the moment of completion of the movement of said mechanism in an 95 opposite direction. In this manner a greater speed in the feeding of the strip in the machine is insured, and the strip will be fed always a uniform distance, thereby preventing the formation of strips of varying lengths 100 and the avoidance of slow speed in the feeding by the machine.

The cutters or shears of the machine A are constructed and operated so that at the moment when the case D' strikes the rear stop 105 a^4 the strip is cut. The further movement of the head d of the shaft a rearward now opens the jaws b , and the strip cut off is dropped from the gripping mechanism D and may be removed from the machine in any 110 suitable manner.

Having thus described the nature and objects of my invention, what I claim as new, and desire to secure by Letters Patent, is—

1. In a mechanism of the character described, a case having a limited range of reciprocatory movement, a gripping and feeding mechanism carried by said case, mechanism for reciprocating the case, means for limiting the movement of the case independently of the full movement of the reciprocating mechanism, and means controlled by the reciprocating mechanism during its movement independent of the case arranged to operate the gripping and feeding mechanism 125 only during said independent movement.

2. In a mechanism of the character described, a case, a rail or guide whereon the case is arranged to reciprocate, two jaws pivoted within the case, a shaft, a head formed 130 on said shaft and extending within the case, means for locking the head to the case during either movement of the case, means for shifting the head in the case at the end of

each reciprocation of said case, and mechanism controlled by the head arranged when the head is shifted in the case to open and close the jaws.

5 3. In a mechanism of the character described, a case, two gripping-jaws pivoted within the case, springs adapted to separate said jaws, a shaft arranged to reciprocate the case, a head formed on said shaft and arranged to slide within the case at or near the end of each reciprocatory movement of said case, and toggles or links connecting the

head with the gripping-jaws, said toggles or links adapted as the head is shifted in one direction to close the jaws against the tension 15 of the springs.

In testimony whereof I have hereunto set my signature in the presence of two subscribing witnesses.

WILLIAM FEHR.
